UNITED STATES PATENT OFFICE.

ANDREW B. SMITH, OF CONCEPCION, CALIFORNIA.

ROTARY ENGINE.

1,387,949.

Specification of Letters Patent. Patented Aug. 16, 1921.

Application filed July 29, 1916. Serial No. 112,140.

To all whom it may concern:

Be it known that I, ANDREW B. SMITH, a citizen of the United States, residing at Concepcion, county of Santa Barbara, State of California, have invented certain new and useful Improvements in Rotary Engines, whereof the following is a specification.

This invention relates to rotary steam engines.

10 In its main features, the invention includes a hollow cylinder, which is divided into two parts by an interior diaphragm. This diaphragm serves also to connect the cylinder with the central shaft, so that the rotation of one determines the rotation of the other. The cylinder is mounted in a suitable casing and provided with a throttle valve, which serves to turn the steam on and off, and also to direct it to one or the other of the divisions of the cylinder. Upon the periphery of the cylinder are secured the piston vanes. The arrangement is such that the steam coming from the throttle valve chest enters the interior of one end of the cylinder and passes thence through suitable ports into the space outside the cylinder where it acts upon the pistons and rotates the cylinder and shaft. This steam passes through other ports into the interior of the other end of the cylinder and thence out through suitable channels and through the other portion of the valve chest to the exit.

Other important features of the invention and the details of construction will be hereinafter described and are shown in the accompanying four sheets of drawings in which I have illustrated an embodiment of my invention and in which,—

Figure 1 is a vertical sectional elevation, 40 the section being taken through the axis of the engine.

Fig. 2 is a cross-section upon the line 2, 2, of Fig. 1, looking in the direction of the arrows.

45 Fig. 3 is a longitudinal section taken at right angles to Fig. 1, and through the line 3, 3, of Fig. 2.

Fig. 4 is a longitudinal section, showing the interior of one end of the hollow cylinder for the purpose of showing the cut-off device by which the steam is caused to act more or less expansively, as desired. The section is taken on line 4, 4, of Fig. 5, looking in the direction of the arrow.

55 Fig. 5 is a section taken on the line 5, 5, of Fig. 4, looking in the direction of the ar-

row, also for the purpose of showing the cut-off.

Fig. 6 is an end view of the hollow cylinder.

Fig. 7 is an elevation partly in section of the throttle valve.

Fig. 8 is a view of one end of the same.

Fig. 9 is a cross-section of the same taken upon the line 9, 9, of Fig. 7, looking in the direction of the arrow.

Fig. 10 is an elevation of one of the rotary valves, which confine the action of the steam to one side of the piston vanes.

Fig. 11 is an end view of the same.

Fig. 12 is an elevation of one of the piston vanes, one-half of it being removed to show the packing, the point of view being indicated by the line 12, 12, in Fig. 13, looking in the direction of the arrow, and

Fig. 13 is a cross-section of the same taken on the line 13, 13, of Fig. 12, looking in the direction of the arrow.

In these figures, 1 represents a casing which may be made in two or more parts secured together by flanges and bolts as at 2. In the upper part of this casing is a valve chest 3, provided with a steam inlet 4, and a steam outlet 5. The interior of this valve chest is circular, and in it is fitted a circular throttle valve which is controlled by the stem 6 and hand-wheel 7. This valve includes an oblique diaphragm 8, which is provided with packing rings 9 at the points where it contacts the walls of the valve chest. Between these points is the mutilated cylindrical portion 10, the opening in which at 11 may be brought by turning the hand-wheel 7, to register with either the port 4 of the port 5. If in register with the port 4, the steam enters through the inlet 4 into the valve chest at the end next the valve stem, and thence passes, as indicated by the arrow in Fig. 1, through the channel 12 to the hollow cylinder. If the valve be turned 95 so that the portion 11 registers with the pipe 5, then the channel 12 becomes an exhaust channel and the steam entering the other side of the diaphragm through a second mutilation of the valve cylinder, enters the 100 channel 13 and thence to the other end of the hollow cylinder. In the position shown in Fig. 1, the valve occupies an intermediate position, and the steam is shut off.

The drive shaft 14 of the engine is mounted in bearings 15 in the ends 16 of the casing 1.

The hollow cylinder or motor cylinder 17, as it may be termed, has at its ends rings 17' contacting members 16, and provided with packing rings 18. This cylinder 17 is divided interiorly by the diaphragm 19, which is provided with a central boss secured upon the shaft 14, so that these parts rotate together. Cylinder 17 is thus divided into two portions, which may be equal or approximately so. Assuming now, that the steam is entering through the channel 12, it enters into the left-hand end of the cylinder 17 through the port 20, and fills that end of the cylinder. From there, it passes out through a circumferential port 21, shown more particularly in Fig. 2, into the circumferential space behind the adjacent piston vane 22. In this action, the steam is confined by the rotary valve 23, which is mounted in the engine casing. This valve is in the form of a crescent, as seen in Fig. 2, and rotates to permit the passing of the piston; but when it has passed, closes the space behind it. The steam acting upon the piston, fills the longitudinal space circumferential to the motor cylinder, and enters the opposite end of the latter through the circumferential ports, shown in dotted line 24 of Fig. 2. From this opposite end of the motor cylinder, the steam passes through the port 25 into the channel 13, and thence out through the exhaust pipe 5.

To reverse the direction of motion of the engine, it suffices to turn the throttle valve 35 by means of the hand-wheel 7, so as to reverse the direction of motion of the steam, causing it to enter channel 13 into the right-hand end of the motor cylinder, and thence to the left-hand end and out through the channel 12, as already indicated.

The rotary valves 23, of which there may be two, opposite to each other, are supported by stub shafts or trunnions 26. Upon these trunnions, at one end, are toothed pinions 27, shown in Fig. 3, which mesh with a spur gear 28 upon the engine shaft 14, so that the motor cylinder and the valves will have the proper synchronous movement. In furtherance of this result, the valve 23 and the motor cylinder 17 may be provided with teeth or serrations 29, as seen more particularly in Fig. 2.

For the purpose of economy, and in order to use the steam expansively, I provide a cut-off arrangement which I will now describe. 30 are sliding panels which fit against the interior circumference of the motor cylinder and serve to close the ports 21 at a desired intermediate point of the movement of the piston, so that the first action of the steam is under full head, and any desired degree of its later action is under its expansive force. These panels are controlled by curved racks 31, which are engaged by pinions 32 on arbors 33. The

arbors extend through the ends of the casing and are controlled by handles 34. The sliding panels 30 are supported by the arms or disks 35 and 36, which may have a tubular connection 37 with each other, which 70 tubular connection surrounds and protects the shaft 13 from the action of the steam.

By way of packing the piston vanes, they may be composed of double walls 38 mounted upon the circumference of the motor cylinder, and embracing between them a sheet of packing material 39, which may be held in place by a pin or bolt 40, shown in Fig. 13.

Referring now to Fig. 2, it will be observed that the space 41 is full of steam, which has not yet begun to exhaust, but is balanced against the two piston vanes in front of and behind it. The space 43 is just beginning to exhaust from behind the valve 23 and to take live steam in front of that valve, and a remnant of steam from the previous stroke still fills the valve space, thus, to that extent, economizing the steam consumption. The space 42 is taking live steam in front of the valve and exhausting from behind it. At 44 is a port (see Fig. 1) for drawing off water of condensation, which may be closed by a plug 45.

Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the spirit of the invention.

What I claim and desire to secure by Letters Patent of the United States, is the following, to-wit:

1. A rotary engine comprising a casing, a hollow motor cylinder within said casing, divided interiorly into two longitudinal parts by a cross diaphragm integrally formed with said cylinder, said parts adapted to act as steam passages.

2. A rotary engine, comprising a casing, a hollow motor cylinder within said casing, divided interiorly into two longitudinal parts, one of said parts communicating with the live steam passage and acting as a continuation thereof, and the other of said parts communicating with the exhaust passages and acting as a continuation thereof.

3. A rotary engine comprising a casing, a hollow motor cylinder within said casing, divided into two longitudinal parts by a cross diaphragm integrally formed with said cylinder, said parts adapted, respectively, to receive live and exhaust steam, and means for directing the steam into one

or other of said parts, thereby reversing its motion and the direction of motion of the engine.

4. A rotary engine comprising a casing, 5 a hollow motor cylinder within said casing, divided into two longitudinal opposite parts mounted upon a longitudinal drive shaft and inclosed within said casing, rotary valves within said casing, piston vanes 10 mounted upon the exterior of said motor cylinder engaging said valves and adapted to establish communications between said parts.

5. In a rotary engine, an inlet and an outlet located in the same plane, a rotary combined throttle and directing valve having an oblique diaphragm engaging said inlet and outlet and a mutilated hollow cylin-

der supported and oscillated by said diaphragm.

6. In a rotary engine, a hollow motor cylinder, having ports and piston vanes upon its exterior in combination with sliding cut-off panels upon its interior surface, a curved rack and pinion within said cylinder engaging said rack and adapted to move said cut-off panels into different positions of adjustment for closing said ports.

In testimony that I claim the foregoing I have hereto set my hand in the presence 30 of two witnesses, this 24 day of July, 1916.

ANDREW B. SMITH.
